2 Claims. (Cl. 264—107)

This invention relates to a method for producing gramophone records with an illustration applied to one side.

The methods known so far for the production of image records have not proved satisfactory because they get out of shape with the known method of production or become wavy. A further point leading to the unsuccessful performance of such records, resides in the fact that the high pressure necessary for converting thermoplastic resin into records damaged the illustrations to be included and became torn by the unavoidable lateral displacement of material during the pressing process.

It is the purpose of this invention to combine an illustration independently of the grooveless area with label with a record in one piece and to protect the illustration against damage. A further object of the invention is to produce an illustrated record, the surface of which acts anti-statically. This object can be achieved in accordance with the invention by surrounding the illustration with a transparent recording material in a greater thickness than the one of the coated tone-foil. The life of the record corresponds to the duration of a tone record of multiple performance. The duration corresponds several times to the duration of a tone foil. The tone groove is not applied to the outer layer under heat and simultaneous pressure as heretofore, but by pressing the heated recording material by cooling off the pressing mold.

It has been surprising to ascertain (and this could not be foreseen) that a sound record produced in accordance with this invention practically does not possess any electrostatic power of attraction. Thus the disturbing particles of dust are not attracted thereto as has been the case with the usual records.

If records are produced without inclusion of an illustration, such records possess very strong electrostatic powers of attraction. It is surprising to notice that the inclusion of an illustration in accordance with this method makes these powers disappear, which contributes largely to the elimination of reproduction interference, caused by particles of dust.

The application of an illustration, independent in its size of the grooveless surface and related to the piece of music, has in addition to its sales appeal, the advantage that the record can be distinguished much easier from another record of a different subject than is the case of well-known records containing a label limited in size and application.

The method covered by this invention for the production of pressed and sprayed records is characterized that the illustration is not applied to the intermediate layer, but coated with a transparent outer layer. The latter completely shuts off the illustration from the outside and it adheres firmly and especially insolubly to the illustration. Furthermore, the groove is not applied to the outer layer as usual under previous heat and pressure, but only

2

by pressing the pre-heated material according to the cooling-off method.

The illustration as well as the recording material can be inserted before the application of the grooves between 5 the image and the matrix in accordance with the pressing method by means of a pressing form having only a matrix with one groove.

The pressing method by means of a pressing form with matrixes having two grooves, calls for polyvinylchloride-foil of 0.75 mm. of thickness to be put in the form, the illustration to be covered with the same foil. In accordance with the invention, the pressing form is simply pressed slightly with the synthetic-resin-press with a temperature brought up to 120° C. and pressed subsequently 10 under cooling with a pressure of 80 tons for each 25 cm. of the record diameter. When the temperature has gone down to a certain level, the form is opened. The material squeezed out at the edges is removed and the record taken out of the form.

With the spraying method the illustration can be fixed 15 in the spraying form in such a way as to be surrounded by the material sprayed in. However, it can also be stretched in its middle in the spraying form and surrounded by the recording material sprayed in as far as the edge of the 20 stretching apparatus.

For producing the record, a suitable synthetic resin or a mixture of same can be used.

The method may be illustrated diagrammatically as 25 shown in the accompanying drawing, in which the four steps are numbered 1 to 4 to illustrate the various steps of the method for the production of a composite sound record which has sound grooves therein. Step #1 shows the picture bearing carrier 2 which is placed between plastic foils 1, and step 2 shows the two foils with the 30 carrier there between placed between a press mold indicated by reference characters 3 and 4 of which the press mold part 3 has negative sound grooves on the surface 5. The mold is closed as shown in step 3 and heat is then applied to the mold portions 3 and 4 to thus press the foils 35 to the carrier 2 with a slight press action. By heating the mold, the heat is transferred to the foils until the foils have reached plastic state. Then the heating is terminated and simultaneously full press power is applied to the foils, 40 step #4, by the press members 3 and 4 with the mold parts 3 and 4 cooled off and thus the composite sound record is produced which is embossed with the surface positive sound grooves on at least one side.

What I claim is:

1. A method for the production of a composite sound record bearing sound grooves the record being produced from at least two transparent plastic foils with a picture bearing carrier being inserted between the foils and with the picture being visible from at least one side of the record, the method comprising placing the foils and the intermediate picture bearing carrier into a press mold which has at least one press surface bearing surface negative sound grooves, closing the press mold so as to slightly press together the foils and the picture bearing carrier, heating the mold so as to thereby transfer heat to the foils 50 until the foils have reached a plastic state, terminating heating, and then simultaneously applying full press power to the foils and the picture bearing carrier while cooling off the mold, whereby a composite sound record is produced which is embossed with surface positive sound 55 grooves on at least one side.

2. A method according to claim 1 wherein said foils are composed of polyvinylchloride having a thickness of 0.75 mm.
